COKING RETORT OVEN

Joseph van Ackeren, O'Hara Township, Allegheny County, Pa., assignor to The Koppers Company of Delaware, a corporation of Delaware

Application June 10, 1932, Serial No. 616,443

15 Claims. (Cl. 202—142)

My invention relates to coking retort ovens and particularly to horizontal ovens such, for example, as those of the Becker crossover type.

An object of my invention is to provide a coke oven battery that is divided into a suitable and convenient number of units for expansion that shall be substantially coincident with operating units of the battery.

Another object is to provide a simple construction in which the ducts for combustible media or waste gases are not intersected by expansion joints or other openings whereby counterflow and leakage of gases are substantially avoided.

It is well known that it is necessary to provide coke oven batteries with a series of transverse expansion joints to compensate for the expansion of the materials of which the battery is constructed when the latter is heated. When these expansion joints intersect ducts or flues for combustible media such as coke oven gas, producer gas and air, and ducts for waste gases, leakage may occur between inflow and outflow ducts because of the pressure differential between them. Such leakage is not only wasteful but dangerous because of the possibility of explosions.

In accordance with the present invention, the regenerators and their connections to the flame flues of cooperating heating walls are arranged in units that are separable by expansion joints without intersection by the latter of any of the flues or ducts for gases. In the preferred form of my invention, each expansion unit consists essentially of one heating wall, two endwise aligned regenerators beneath the heating wall and the ducts and flues between the regenerators and the flame flues of the heating wall.

In a modification, each expansion unit comprises two heating walls and the intervening structure, the regenerators therebeneath and the communicating ducts and flues therefor. Alternate oven chambers are of different widths to compensate for the changes produced by expansion when the battery is heated and the expansion joints are closed. This arrangement permits the connection of each regenerator to the flame flues of two adjacent heating walls instead of a single heating wall as in the preferred arrangement.

In each of the arrangements referred to above, each transverse vertical expansion joint extends into an oven chamber and also into a slot in a pillar wall beneath the oven chamber and which slot is connected to the atmosphere.

The details of my invention will be described

in connection with the accompanying drawings, in which

Figure 1 is a view in vertical, transverse section of a coke oven battery taken partially on line A—A and partially on line B—B of Fig. 2;

Fig. 2 is a longitudinal vertical sectional view of a portion of the coke oven battery and taken on line II—II of Fig. 1;

Fig. 3 is a flow diagram in perspective of two of the heating walls of Figs. 1 and 2 and certain of their associated parts, parts being broken away;

Fig. 4 is a view in transverse vertical section of a modified form of coke oven battery taken partially on line C—C and partially on line D—D of Fig. 5; and

Fig. 5 is a longitudinal, vertical, sectional view of a portion of the coke oven battery of Fig. 4.

Fig. 6 is a horizontal sectional view taken on lines 6—6 of Figs. 4 and 5.

Referring particularly to Figs. 1, 3, and 3a, a coke oven battery 1, constructed in accordance with the preferred form of my invention, comprises a series of horizontal oven chambers 2 that alternate with heating walls 3. Any suitable number of ovens and heating walls may be provided, the number of the heating walls, however, being an even one in order that they may be arranged in pairs, as will be hereinafter described.

The battery is provided with the usual roof or top 4 through which extend charging holes 5 by means of which coal may be charged into the oven chambers. Gas offtake openings 6 at each end of the oven chambers 2 are connected to ascension pipes 7 which communicate with collecting mains 8 extending along the sides of the battery.

Below the oven chambers and heating walls is intermediate brickwork 9 extending horizontally and separating the oven chambers and heating walls from a series of crosswise regenerators 10 and 11 therebeneath. The regenerators 10 and 11 each extend half the width of the battery, a regenerator 10 and a regenerator 11 being in endwise alignment.

The regenerators 10 are provided with sole flues 12 that are connected to reversing boxes 13 to which producer gas is supplied by means of a producer gas main 14 and from which combustion gases are conducted into a vertical duct 15 connected to a waste gas main 16. Each reversing box 13 also has an air damper 17 that is closed when producer gas is used.

The regenerators 11 which are also supplied with sole flues 12 are connected to reversing

boxes 18 having an air damper 17 and are also connected by means of a vertical duct 15 to a second waste gas main 16. From the foregoing it will be noted that the regenerators 10 operate only to conduct fuel gas in one direction of flow and waste gases in the other direction while the regenerators 11 conduct air when they operate as inflow regenerators and conduct waste gases when operating as outflow regenerators.

10 Two coke oven gas mains 19 located on the respective sides of the battery supply coke oven gas, when the latter is used as fuel, through gas guns 20 and horizontal ducts 21 to the flued heating walls.

15 Each of the heating walls 3 is provided with a series of vertical flame flues 22 that are connected at their tops by ducts 23 to a horizontal flue 24. The upper horizontal flues 24 of adjacent heating walls are connected by means of a series 20 of crossover flues 25 which thus arrange the flame flues of the heating walls in pairs for operation in series. This construction is a feature of the well known Becker type of horizontal coke ovens.

25 Beneath each heating wall and extending horizontally parallel thereto for its entire length are two relatively large horizontal flues 26 and 27 that are connected by means of ducts 28 to the regenerators 10 and 11 respectively. Each horizontal flue 26 and 27 is also connected by means of inclined ducts 29 to each of the flame flues of the heating wall directly above it.

30 Beneath each oven chamber 2 is a pillar wall 31 for supporting the structure above the regenerators and for separating the crosswise regenerators from each other. Each pillar wall 31 is provided with a slot 32 which extends substantially throughout the length and height of the wall and upwardly through the intermediate brickwork adjacent to the bottom of the oven chamber immediately above it. The slots 32 open into the atmosphere in the same manner illustrated in connection with the slots 44 in Fig. 4.

35 The top of each slot 32 is connected by means of expansion joints 33 to the bottom of each oven chamber. The top of the battery is also provided with a series of expansion joints 34 and 35 in order that expansion of the roof may correspond to the expansion of the structure below.

40 When the battery is heated the expansion of the several units constituted by the divisions of the pillar walls 31 by means of the slots 32 and the expansion joints 33, 34, and 35 is compensated for by the reduction in the spaces in the slots and the several expansion joints. Inasmuch as each expansion unit is complete in itself insofar as concerns the regenerators, the flame flues to which they are connected, and the communicating ducts and flues therebetween, these ducts and flues are not affected by such expansion and there is therefore little likelihood of leakage as may be the case when expansion joints intersect such ducts and flues.

45 In the operation of this form of my invention it may be assumed that producer gas is being used as fuel and that the flow of gases through the regenerators 10 is as indicated in Fig. 2, which is typical of all of the regenerators 10 of the battery. The regenerators 10 conduct gases in accordance with the legends G and WG which indicate, respectively, fuel gas and waste gases.

50 On the other side of the battery the regenerators 11 will operate in a similar arrangement, half of the regenerators conducting air and the other half of the regenerators conducting waste gases.

The inflow regenerators 10 conduct producer gas into the horizontal flues 26 connected thereto and the inflow regenerators 11 conduct air simultaneously into the horizontal flues 27 connected thereto and fuel gas and air are supplied to each of the flame flues 22 of one heating wall of each connected pair for burning upwardly therein. The gases of combustion pass through ducts 23 into the horizontal flues 24 and thence through crossover flues 25 into the corresponding structure 10 of the adjacent heating wall of each pair.

The hot gases are then distributed in reverse order through the heating system of the connected heating wall and the gases flow through the connected horizontal flues 26 and 27 and the corresponding outflow regenerators 10 and 11 to the waste gas mains 16, as will be understood. A representative pair of heating walls is diagrammatically shown in Fig. 3 and the operation of each pair of heating walls corresponds thereto.

The direction of flow of gases in the battery is reversed periodically by the usual reversing mechanism and the inflow regenerators 10 now become outflow regenerators and the former outflow regenerators now become inflow regenerators, as indicated by the legends G and WG in dotted lines in Fig. 2. A corresponding change occurs in the regenerators 11 on the other side of the battery in that the air inflow regenerators become waste gas outflow regenerators and vice versa.

45 When coke-oven gas is used as fuel it is supplied to one heating wall of each pair through the gas guns 20, ducts 21 and nozzles 37 for the respective flame flues 22. All of the inflow regenerators 10 and 11 now supply air to the flame flues 22 and the operation is as otherwise described for producer gas. Upon reversal, combustible media is similarly supplied to the other heating wall of each pair and the flow of gases throughout the battery is correspondingly reversed.

50 A modified form of my invention is illustrated in Figs. 4 and 5 in which similar numerals designate corresponding parts. The essential difference in this latter form of my invention comprises the arrangement of the regenerators and their connections to the heating walls in such manner that each expansion unit comprises two heating walls and two regenerators that are arranged side by side.

55 Cross regenerators 40 are arranged in pairs between pillar walls 41 and these regenerators extend the entire width of the battery. The regenerators 40 are each provided with two sole flues 42 in order to provide a proper distribution of the incoming air or producer gas, as the case may be, throughout the checkerwork of the regenerators. Each regenerator is connected to each of the flame flues of each of two adjacent heating walls to supply either producer gas or air thereto or to receive waste gases therefrom.

60 The members of each pair of regenerators 40 are separated by a partition wall 43. This latter wall may be of sufficient strength to support the structure thereabove but its thickness need not be great for the purpose of separating the regenerators inasmuch as the members of each pair of regenerators always conduct gases in the same direction, and there is, therefore, substantially no pressure differential between them.

65 Each pillar wall 41 is provided with a slot 44 substantially similar to the slot 32 of the preferred form of my invention in that it extends substantially from the base of the battery through

the horizontal brickwork and is connected by expansion joints 45 to the bottom of the oven chamber 2 thereabove. The slots 44 open into the atmosphere, as shown in Fig. 4, in order to prevent leakage between adjacent inflow and outflow regenerators. Expansion joints 46 and 47 at the top of the battery provide for expansion to correspond with that occurring in the expansion joints 45 and the slots 44.

10 In the construction of the battery alternate oven chambers 2 that are directly above the pillar walls 41 are constructed slightly wider than the remaining oven chambers that are not connected to expansion joints. This arrangement provides 15 that when the battery is heated expansion of the refractory material causes the closing of the expansion joints and the width of the initially wider ovens to be diminished until they are substantially the same width as the other ovens which 20 have slightly increased in width because of expansion of the materials of their walls.

In the operation of the modified form of battery, producer gas is supplied by the producer gas main 14 through reversing boxes 13 to the sole 25 flues 42 of the inflow regenerators for preheating producer gas. Air is admitted through adjacent reversing boxes 13 to air inflow regenerators, the arrangement of the regenerators for carrying gas, air and waste gases being that indicated in Fig. 5, these gases being respectively indicated by the legends "Gas", "Air", and "WG".

Gas and air are supplied by pairs of regenerators 40 through ducts 49 to the flame flues of each of two adjacent heating walls thereabove for burning upwardly therein, and waste gases pass 30 through the connected cross-over flues 25 into the flue systems of the adjacent heating walls in series therewith and waste gases pass out through the pair of regenerators connected to the other member of each pair of heating walls.

When the flow of gases in the battery is reversed, as occurs periodically, the inflow regenerators become outflow regenerators, and vice versa, the arrangement now being that indicated by the legends in dotted lines in Fig. 5. It will be noted 45 that the same arrangement of the regenerators is maintained in that both regenerators of each pair are always inflow or outflow regenerators. It may be noted also that an air regenerator is always between a producer gas generator and a waste gas generator in both directions of flow of gases.

It will be noted that in the coke oven battery just described each expansion unit comprises two 50 regenerators, two heating walls and the structure therebetween, and that the expansion joints forming the boundary of each expansion unit do not intersect any of the ducts or flues for carrying combustible media or waste gases. This arrangement substantially prevents any leakage or 55 counterflow between combustible media and waste gases.

It will also be noted in this form of my invention that by reason of the full length of the regenerators only a single waste gas main and a single producer gas main are required. It has also been arranged to supply coke oven gas from one side of the battery only, the horizontal duct 21 connected to the gas gun 20 extending the entire width of the battery for supplying each heating wall.

The advantages of the preferred form of my invention are that the battery is divided into relatively small units for expansion and each of these units is complete insofar as concerns the regen-

erators, the adjacent heating walls and the flues and ducts for connecting the regenerators to the flame flues of the heating walls. This arrangement provides that the expansion of the battery may occur without disturbing any of the communicating ducts and flues, and leakage between ducts for conducting combustible media and waste gases is thereby substantially entirely avoided. 5

The arrangement of the regenerators whereby air is supplied on one side of the battery only 10 and producer gas is supplied on the other side of the battery only together with the horizontal flues connected to the regenerators and extending the width of the battery require that only one producer gas main be employed. This arrangement of expansion units is particularly adapted 15 for use in batteries of the Becker crossover type of horizontal ovens inasmuch as each heating wall of a connected pair for operation in series may be part of an expansion unit without in any 20 way interfering with the operation of the heating wall in series therewith and which may be a part of another expansion unit.

In the modified form of my invention the expansion units are somewhat wider but the regen- 25 erators extend the entire width of the battery and each regenerator is arranged to alternately supply combustible media to two adjacent heating walls and to receive waste gases from these heating walls.

30 The elimination of one of the coke oven mains, a producer main and a waste gas main is of advantage also in that it reduces the cost of construction and is a considerable convenience in the operation of the battery.

35 The foregoing and other advantages of construction and operation will be apparent to those skilled in the art relating to coke ovens.

I claim as my invention:

1. A coking retort oven battery comprising a 40 plurality of horizontal oven chambers and heating walls therefor and alternating therewith side by side in a row, vertical flame flues in said heating walls, an expansion joint extending from adjacent the top of each coking oven chamber to 45 substantially the top of the oven, regenerators extending beneath said heating walls and parallel thereto and connected in series with the flame flues of adjacent heating walls by means of ducts, horizontally extending walls extending beneath 50 and parallel to said oven chambers and between said regenerators, expansion accommodating slots in certain of the regenerator walls that are between two contiguous regenerators and common to both, and extending substantially throughout 55 the length and height of the regenerator chambers, and expansion joints extending from the tops of said slots to the bottoms of the coking chambers thereabove without the intersection of said ducts by said slots or said expansion joints, said 60 expansion joints being closed to the regenerator chambers and leading to said slots whereby the battery structure is divided into expansible units for expansion when the oven is heated, each unit comprising at least one regenerator, one flued 65 heating wall and the communicating ducts therebetween.

2. A coking retort oven battery comprising a 70 plurality of horizontal oven chambers and heating walls therefor and alternating therewith side- 75 by-side in a row, vertical flame flues in said heating walls, crossover flues crossing over certain of said coking chambers for connecting the flame flues of adjacent heating walls in series and thereby arranging said heating walls in pairs, an 75

expansion joint extending from adjacent the top of each coking oven chamber to substantially the top of the oven, regenerators extending beneath said heating walls and parallel thereto and connected in series with the flame flues of adjacent heating walls by means of ducts, horizontally extending walls extending beneath and parallel to said oven chambers and between said regenerators, expansion accommodating slots in the regenerator walls that are both beneath the coking chambers crossed over by the crossover flues and are between two contiguous regenerators and common to both, said slots extending substantially throughout the length and height of the regenerator chambers, and expansion joints extending from the tops of said slots to the bottoms of the coking chambers thereabove without the intersection of said ducts by said slots or said expansion joints, said expansion joints being closed to the regenerator chambers and leading to said slots, whereby the battery structure is divided into expansible units for expansion when the oven is heated, each unit extending in length transversely across the battery and in width including at least one regenerator and one heating wall thereabove and the ducts for communication therebetween.

3. A coking retort oven battery comprising a plurality of horizontal oven chambers and heating walls therefor and alternating therewith side-by-side in a row, vertical flame flues in said heating walls, crossover flues crossing over alternate coking chambers only for connecting the flame flues of adjacent heating walls in series and thereby arranging said heating walls in pairs, and expansion joint extending from adjacent the top of each coking oven chamber to substantially the top of the oven, regenerators extending beneath said heating walls and parallel thereto and connected in series with the flame flues of adjacent heating walls by means of ducts, horizontally extending walls extending beneath and parallel to said oven chambers and between said regenerators, expansion accommodating slots in the regenerator walls that are both beneath the coking chambers crossed over by crossover flues and are between two contiguous regenerators and common to both, said slots extending substantially throughout the length and height of the regenerator chambers, and expansion joints extending from the tops of and forming a continuous expansible connection with said slots to the bottoms of the coking chambers thereabove without the intersection of said ducts by said slots or said expansion joints, said joints being closed to the regenerator chambers and leading to said slots, whereby the battery structure is divided into expansible units for expansion when the oven is heated, each unit extending in length transversely across the battery and in width including at least one regenerator and one heating wall thereabove and the ducts for communication therebetween, and each of said slots opening into the atmosphere whereby leakage of gases from one expansion unit to another is effectually prevented.

4. A coking retort oven battery comprising a plurality of horizontal oven chambers and heating walls therefor and alternating therewith side-by-side in a row, vertical flame flues in said heating walls, an expansion joint extending from adjacent the top of each coking oven chamber to substantially the top of the oven, regenerators extending beneath said heating walls and parallel thereto and connected in series with the flame

flues of adjacent heating walls by means of ducts, horizontally extending walls extending beneath and parallel to said oven chambers and between said regenerators, expansion accommodating slots in certain of the regenerator walls that are between two contiguous regenerators and common to both, and extending substantially throughout the length and height of the regenerator chambers, and expansion joints extending from the tops of said slots to the bottoms of the coking chambers thereabove without the intersection of said ducts by said slots or said expansion joints, said expansion joints being closed to the regenerator chambers and leading to said slots, whereby the battery structure is divided into expansible units for expansion when the oven is heated, each unit comprising two regenerators which operate to supply fuel gas and air respectively when operating as inflow regenerators and both of which conduct waste gases when operating as outflow regenerators and each unit comprising also the flame flues communicating with said two regenerators.

5. A coking retort oven battery comprising a plurality of horizontal oven chambers and heating walls therefor and alternating therewith side-by-side in a row, vertical flame flues in said heating walls, crossover flues crossing over certain of said coking chambers for connecting the flame flues of adjacent heating walls in series and thereby arranging said heating walls in pairs, an expansion joint extending from adjacent the top of each coking oven chamber to substantially the top of the oven, regenerators extending beneath said heating walls and parallel thereto and connected in series with the flame flues of adjacent heating walls by means of ducts, horizontally extending walls extending beneath and parallel to said oven chambers and between said regenerators, expansion accommodating means comprising slots in the regenerator walls that are both beneath the coking chambers crossed over by the crossover flues and are between two contiguous regenerators and common to both, said slots extending substantially throughout the length and height of the regenerator chambers, and expansion joints extending from the tops of said slots to the bottoms of the coking chambers thereabove and forming a continuous unbroken expansion means with said slots without the intersection of said ducts by said slots or said expansion joints, said expansion joints being closed to the regenerator chambers and leading to said slots, whereby the battery structure is divided into expansible units for expansion when the oven is heated, each unit comprising a heating wall and two regenerators therebeneath in alignment transversely across the battery and that are each communicably connected to each of the flame flues of said heating wall for supplying air and fuel gas respectively thereto or for conducting waste gases therefrom.

6. A coking retort oven battery comprising a plurality of horizontal oven chambers and heating walls therefor and alternating therewith side-by side in a row, vertical flame flues in said heating walls, crossover flues crossing over alternate coking chambers only for connecting the flame flues of adjacent heating walls in series and thereby arranging said heating walls in pairs, an expansion joint extending from adjacent the top of each coking oven chamber to substantially the top of the oven, regenerators extending beneath said heating walls and parallel thereto and connected in series with the flame flues of adjacent heating walls by means of ducts, horizontally

extending walls extending beneath and parallel to said oven chambers and between said regenerators, continuous expansion accommodating means extending continuously throughout the 5 length and height of the regenerator chambers in the regenerator walls and to the bottoms of said coking chambers and crossed over by cross-over flues and closed to the regenerator chambers for dividing said battery into a plurality of 10 expansible units for expansion, each expansion unit comprising a heating wall, two regenerators in alinement transversely of the battery, and gaseous media distributing means comprising a horizontal duct and communicating ducts for connecting each of said two regenerators to each of the flame flues of said heating wall.

7. A coking retort oven battery comprising a plurality of horizontal oven chambers and heating walls therefor and alternating therewith 20 side-by-side in a row, vertical flame flues in said heating walls, crossover flues for connecting the flame flues of adjacent heating walls in series and thereby arranging said heating walls in pairs, two regenerators in endwise alinement beneath 25 each heating wall and parallel thereto, means comprising a horizontal duct for communicably connecting each flame flue of each of said heating walls to the two regenerators beneath the heating wall, and means for supplying fuel gas 30 to one of said two regenerators and for simultaneously admitting air to the other regenerator and for alternately withdrawing waste gases from both of said regenerators.

8. A coking retort oven battery comprising a plurality of horizontal oven chambers and heating walls therefor and alternating therewith side-by-side in a row, vertical flame flues in said heating walls, crossover flues for connecting the flame flues of adjacent heating walls in series and 40 thereby arranging said heating walls in pairs, two regenerators in endwise alinement beneath each heating wall and parallel thereto, means comprising a horizontal duct for communicably connecting each flame flue of each of said heating 45 walls to the two regenerators beneath the heating wall, and means for alternately supplying fuel gas to or withdrawing waste gases from alternate pairs of regenerators on one side of the battery and for alternately admitting air to or 50 withdrawing waste gases from alternate pairs of regenerators on the other side of the battery.

9. A coking retort oven battery comprising a plurality of horizontal oven chambers and heating walls therefor and alternating therewith side-by-side in a row, vertical flame flues in said heating walls, crossover flues for connecting the flame flues of adjacent heating walls in series and thereby arranging said heating walls in pairs, two regenerators in alinement beneath each heating 55 wall and each extending substantially half the width of said battery, two parallel horizontal ducts extending between said regenerators and the adjacent heating wall, and each of said horizontal ducts communicating with each flame flue of said adjacent heating wall and with one of said two regenerators.

10. A coking retort oven battery comprising a plurality of horizontal oven chambers and heating walls therefor and alternating therewith side-by-side in a row, vertical flame flues in said heating walls, crossover flues for connecting the flame flues of adjacent heating walls in series and thereby arranging said heating walls in pairs, two regenerators beneath each heating wall in alinement lengthwise thereof and each extending sub-

stantially half the width of said battery, two parallel horizontal ducts extending between said regenerators and the adjacent heating wall, each of said horizontal ducts communicating with each flame flue of said adjacent heating wall and with one of said two regenerators, and means comprising a horizontal conduit extending between each of said two parallel ducts for supplying rich gas to the flame flues of said heating wall.

11. In a coking retort oven battery comprising a plurality of horizontal oven chambers and flued heating walls therefor and alternating therewith side-by-side in a row, regenerators beneath said oven chambers and heating walls and parallel therewith, said regenerators being arranged in pairs and both regenerators of each pair communicating with the flues of each of two adjacent heating walls, and pillar walls between said pairs of regenerators and extending beneath alternate oven chambers the improvement comprising a continuous expansion accommodating means in each of said pillar walls extending continuously and uninterruptedly from the base thereof to the bottom of the coking chamber thereabove.

12. A coking retort oven battery comprising a plurality of horizontal oven chambers and heating walls therefor and alternating therewith side-by-side in a row, vertical flame flues in said heating walls, regenerators extending beneath said heating walls and parallel thereto and connected in series with the flame flues of adjacent heating walls by means of ducts, horizontally extending pillar walls extending beneath and parallel to said oven chambers and between said regenerators, an expansion joint extending from adjacent the tops of coking chambers aforesaid to substantially the top of the oven, expansion accommodating slots in certain of the regenerator walls and extending substantially throughout the length and height of the regenerator chambers, and expansion joints extending from the tops of said slots to the bottoms of the coking chambers thereabove without the intersection of said ducts by said slots or said expansion joints and with said joints closed to the regenerators, whereby the battery structure is divided into expansible units for expansion when the oven is heated, each unit comprising at least one regenerator, one flued heating wall and the communicating ducts therebetween, and each of said slots opening into the atmosphere whereby leakage between regenerators on opposite sides of the said pillar walls is prevented.

13. A coking retort oven battery comprising a plurality of horizontal oven chambers and heating walls therefor and alternating therewith side-by-side in a row, flame flues in said heating walls, the flame flues of adjacent heating walls being communicably connected in pairs for gas flow in series, regenerators extending beneath said heating walls and parallel thereto and connected in series with the flame flues of adjacent heating walls by means of ducts, horizontally extending pillar walls extending beneath and parallel to said oven chambers and between said regenerators, said regenerators being arranged in pairs and both regenerators of each pair communicating with the flues of each of two heating walls of an adjacent pair, each of the pillar walls between adjoining pairs of said regenerators having therein a continuous expansion accommodating means comprising a vent passage and an expansion joint extending thereto with the expansion accommodating means extending con-

tinuously from the base of the pillar wall to the bottom of the coking chamber thereabove.

14. A coking retort oven battery comprising a plurality of horizontal coking chambers and heating walls therefor alternating therewith side-by-side in a row, flame flues in said heating walls, flow duct means for communicably connecting the flame flues of the heating walls in two sets operable in alternation with each other for inflow 10 combustion and outflow of combustion products, an expansion joint extending from adjacent the top of each coking chamber to substantially the top of the oven, regenerators beneath each heating wall and in alinement lengthwise thereof, 15 two parallel horizontal ducts extending between said regenerators and the adjacent heating wall, and each of said horizontal ducts communicating with flame flues of said adjacent heating wall and with one of said regenerators, regenerator 20 walls beneath said coking chambers, and expansion accommodating means in regenerator walls which are beneath the coking chambers and which lie between and are common to each of two contiguous regenerators, said expansion accom- 25 modating means comprising vent passages and expansion joints extending to the bottoms of the coking chambers for dividing the battery structure into expandible expansion units each of which comprises a heating wall, the regener-

ators therebeneath and the ducts communicating with said regenerators.

15. A coking retort oven battery comprising a plurality of horizontal coking chambers and heating walls therefor alternating therewith side-by-side in a row, flame flues in said heating walls, regenerators extending beneath said heating walls and parallel thereto and connected in series with the flame flues of adjacent heating walls by means of ducts, horizontally extending pillar walls 10 extending beneath and parallel to said coking chambers and between said regenerators, and means for dividing the battery structure into a plurality of expandible units for expansion when the structure is heated, said means comprising expansion joints extending from adjacent the top of the coking chambers to substantially the top of the oven and expansion accommodating slots in certain of the pillar walls and extending substantially through the length and height of the regenerator chambers and expansion joints extending from the tops of said slots to the bottoms of the coking chambers thereabove without the intersection of said duct by the slots or said expansion joints, whereby 15 the battery structure is divided into expandible units for expansion when the oven is heated. 20 25

JOSEPH VAN ACKEREN.
